SELECTOR MECHANISM

Georges Xavier Lens, Antwerp, Belgium, assignor
to International Standard Electric Corporation,
New York, N. Y., a corporation of Delaware

Application March 24, 1950, Serial No. 151,593
In France April 1, 1949

6 Claims. (Cl. 74—483)

1

The present invention relates to a controlling or selecting mechanism using mechanical clutching.

It is based upon the use of an arrangement comprising a movable member successively placed under the dependence of two controlling bars, having been the object of the U. S. patent application filed by the applicant on December 31, 1949, Serial No. 136,188 (G. X. Lens 39).

The object of the invention is the constitution of a combination of multiple controlling or selecting mechanisms permitting to obtain the displacement, in two directions, of control devices and to cause, for each of these displacements, a predetermined action. This combination can, for instance, be used as a mechanical selector for the constitution of selector switches such as those provided in telecommunication, telesignaling, telecontrol installations or similar installations.

Another object of the invention is the realization of an assembly of different constituting members to form a combination which has a reduced volume while permitting a large number of controlling or selecting actions.

One of the characteristics of the present invention resides in a controlling or selecting mechanism constituted by the combination of two bars, one vertical, the other horizontal, movable in the longitudinal sense, of a movable member, constituting a clutch member which, in the rest position, is under the control of the vertical bar and, when the said vertical bar comes into a working position, under the control of the horizontal bar, of a controlling device actuated by the movable member during its displacement by the horizontal bar, the said controlling device being able to occupy two different positions according to the sense of displacement of the horizontal bar and acting, either directly or indirectly, upon the device to be controlled, means being provided to return the control device to its rest position when the freed horizontal bar is itself returned to its rest position.

Another characteristic of the present invention resides in the fact that a movable member constituting the clutch member, having been placed under the control of a horizontal bar by means of a vertical bar coming into a working position and, the said horizontal bar coming into a working position, the vertical bar can be returned to a rest position and be used for other selections.

Another characteristic of the invention resides in the fact that the lever arm which is a constituting part of a controlling device, comprises

2

at its end a slot which is located in front of a slot provided in the horizontal bar, both said slots being designed to receive the movable member which causes the clutching of the lever and of the horizontal bar.

Another characteristic of the invention resides in the provision of fixed pieces having a profiled shape, fixed vertically on both sides of a supporting plate and regularly spaced, between

- 10 which, movable vertical bars are displaced and laterally guiding the movable members, on one hand, when the said movable members are in a rest position in their slots provided in the vertical bars, and on the other hand when the said 15 movable members are in a working position during the displacement of the movable horizontal bars.

- Another characteristic of the invention resides in horizontal fixed pieces having a profiled shape, 20 on which the movable horizontal bars are sliding during their displacements, the said horizontal fixed pieces comprising at their upper part an inclined plane on which the movable members are rolling to return to their rest position in 25 the slots provided in the movable vertical bars during the return of the movable horizontal bars to the rest position.

- Other characteristics will become more apparent from the following description which is 30 given as a non-limitative example, with reference to the appended figures which represent:

Fig. 1 is a perspective view of part of a combination of controlling or selecting mechanism on which only those parts necessary for a good 35 understanding of the operations have been represented, some of these parts being represented in cross-sectional views to show also how they are dependent upon one another and the way in which they are assembled;

- 40 Figs. 2a, 3a, and 4a, a cross-sectional side view of a ball controlling or selecting mechanism respectively: in the rest position, the vertical bar in the working position, the horizontal bar and the controlling device in the working position, 45 the vertical bar having been returned to the rest position;

- Figs. 2b, 3b and 4b, cross-sectional plan views corresponding respectively with Figs. 2a, 3a and 4a.

- 50 Referring to Fig. 1, it will now be described how a controlling or selecting mechanism is constituted.

A movable vertical selecting bar such as 1, having an appropriate cross-section, comprises 55 slots such as 2, in which movable members con-

3

stituted by balls such as 3 are located. Each slot 2 comprises at its lower part an inclined part 4. The lower part of the vertical bar 1 is terminated by a shoulder piece 5 having an L-shape, as represented on the figure, by means of which the said bar comes to rest, in the rest position, upon a fixed plate 6. The lower end of the bar 1 comprises a slot 7, profiled as indicated on the figure, by means of which the said bar is made mechanically dependent upon an appropriate device, not shown, controlling its vertical translating movement.

A spring 8 which rests on one hand on the lower face of the plate 6, on the other hand, on a shoulder piece 9, fixed to the bar 1, returns the said bar from its working position to its rest position. The balls such as 3 are laterally guided in their slots such as 2 by the lateral surfaces of fixed vertical pieces such as 10.

A movable horizontal clutch bar such as 11, having a profiled shape as represented on the figure, comprises on one side regularly and laterally spaced indentations such as 12, 12', designed to receive the balls such as 3, from the movable vertical bars such as 1 placed in a working position, and on the other side, openings such as 13, 13' permitting the insertion of lever arms such as 14, 14'. A rib 15 has been made in one of the sides of the horizontal bar 11 in order to make it more rigid. A piece such as 16, ended in the form of a U is assembled at one of the ends of the horizontal bar 11. A slot 17, at the other end of the piece 16, is provided for placing the horizontal bar under the control of an appropriate device, not shown, controlling its longitudinal displacements. The movable horizontal bar 11, for its return to the rest position, is subjected to the action of a resilient device constituted by spring 18, held on one hand in the slot of a fixed vertical bar 19 which goes through the piece 16 by an opening 20 having a buttonhole shape, and on the other hand, in a slot provided in the piece 16, laterally located with respect to the opening 20. The length of the opening 20 is sufficiently large so that the piece 16 does not hinder the displacement of the horizontal bar in one sense or the other.

The movable horizontal bar 11 is supported and guided by a profiled cross piece such as 21, fixed to the vertical fixed pieces 10. More particularly, the said cross piece 21 presents on its upper face an inclined plane 22 on which the balls 3 are rolling to return to their rest position in the slots 2 provided in the movable vertical bars 1.

A controlling device constituted on one hand, by a lever such as 14 having an L shape as represented on the figure, rotating around 23, and comprising two arms 24 and 25, and on the other hand, by a pusher 28, mechanically related to the said lever, acts, by the free end 34 of the pusher 28, either directly, or indirectly, on the device to be controlled, e. g. a commutating device.

The arm 24 of the lever 14, terminated by a fork 26 located in front of the indentations 12 provided in the movable horizontal bar 11, penetrates inside the said bar via an opening such as 13. The lever 14 is made mechanically dependent upon the pusher 28 by the end of the arm 25 which is inserted in an opening 27 provided in the said pusher. A supporting piece 33 having a U shape guides the pusher 28, the said pusher going through the two parallel sides 31 and 32 of the piece 33 by two openings 29 and 30. A re-

4

silient device constituted by a spring 35 located in an opening provided in the pusher 28, returns the controlling device from its working positions to its rest position.

5 It will now be described how a controlling or selecting mechanism is operated.

On Fig. 1, as well as on Figs. 2a and 2b, the various parts of the mechanism are in the rest position. The movable selecting vertical bar 1 is in S₀, the movable horizontal clutch bar 11 in E₀, the pusher 28 in P₀ and the ball 3 in the slot 2, rests against the upper edge 36 of the profiled cross piece 21 (Fig. 2a).

When the vertical bar 1, actuated in an upward direction, along the arrow f₁, by any appropriate controlling device, is brought into its working position S₁ (Figs. 1, 3a and 3b), the ball 3 follows the displacement of the said bar (arrow f₂) and, rolling along the inclined plane 4 comes into the slot 12 and the fork 26 of the lever arm 24 upon the inclined plane 22 of the cross piece 21. The vertical displacement of the bar 1 is calculated in such a manner that the upper edge of the inclined plane is raised above the edge 36 of the cross piece 21 in such a manner that the ball 3 is maintained in its position in the indentation 12 and the fork 26 against the straight part 37 of the movable vertical bar 1.

It will now be assumed that the horizontal clutch bar 11 is actuated in the sense of the arrow f₃ (Figs. 1-4a and 4b), by any appropriate controlling device, and is moved from its rest position E₀ to its working position E₁.

For the displacements of the horizontal bar 11, it will be referred to the displacements shown at the end of the bar 11' (Fig. 1), all the horizontal bars being constituted in an identical manner.

The movable vertical bar 1 is still in the working position S₁. During its displacement, the horizontal bar 11, by the side 38 of the indentation 12 (Fig. 4b), carries away the ball 3 which is then guided by the piece 10 and simultaneously, the ball 3 carries away, by means of the fork 26, the lever 14 which, pivoting around its axis 23, carries away in the sense of the arrow f₃ by its arm 25, the pusher 28 which comes into position P₁ and actuates the controlling device considered.

When the horizontal bar 11 is in the working position, the vertical bar 1 can return to the rest position, without modifying the position of the pusher 28, the ball 3 being maintained in the working position by the horizontal bar 11 and the fixed piece 10.

65 To suppress the action of the pusher 28 upon the controlled device, it is merely necessary to release the action exerted upon the horizontal clutch bar 11 by its controlling device. The horizontal bar 11, under the action of the spring 18, then returns to its rest position E₀, carrying away in its displacement the ball 3 which, being no longer maintained by the fixed piece 10, rolls along the inclined plane 22 of the cross piece 21 and again falls in the slot 2 of the vertical bar 1 in the rest position, returning to the position which it occupied on Figs. 1, 2a and 2b. Simultaneously, under the combined action of the ball 3 and the spring 35, the controlling device (pusher 28 and lever 14) returns to its rest position.

75 When the horizontal bar 11 is actuated in the sense of the arrow f₄ (Fig. 1) and comes into its second working position E₂, the ball 3 following the displacement of the said bar, carries away in its displacement the lever 14 which acts on the

pusher 28 in the sense of the arrow $f'4$, the said pusher 28 coming into working position P_2 .

It will now be described, by referring again to Fig. 1, how the fixed pieces 10 and the cross pieces 21 are constituted and the manner in which these various pieces are interassembled to form a combination of several controlling or selecting mechanisms.

The fixed pieces 10 having a U shape, are provided on the edges of the parallel sides, with slots such as 39 and fixing tags such as 40, arranged in such a manner that a slot 39 alternates with a tag 40 and that a tag on one of the parallel sides is aligned with a slot on the other side.

These pieces 10 are fixed vertically in front of another, on both sides of a central supporting plate 41 in which small openings such as 42 are provided in order to receive the tags 40. On the other hand, the arrangement of the pieces 10 on both sides of the plate 41, is such that to a tag 40 on a piece 10 corresponds a slot 39 on the piece located opposite on the other side of the plate 41, the said slots 39 being provided so as not to hinder the full engagement of the tags 40 in the small openings 42.

The profiled cross pieces 21 on which the horizontal clutch bars such as 11 are sliding, comprise also fixing tags such as 43, regularly spaced as shown on Fig. 1. These tags 43 are introduced into small openings such as 44 provided in the central part of the pieces 10 having a U shape. To consolidate this assembly, these cross pieces 21 are screwed by means of screws such as 45 which go through the said cross pieces 21, via holes such as 46 and are screwed in holes such as 47 provided in the vertical fixed pieces 10.

The movable vertical selecting bars such as 1, are located between the pieces 10, while the horizontal clutch bars such as 11 are resting on each cross piece 21. In such a manner one obtains, in a reduced space, a combination of controlling mechanisms permitting to perform multiple selections among appropriate devices which can, for example, be constituted by commutating mechanisms.

Without leaving the scope of the invention, one could utilize the various elements constituting this combination of controlling or selecting mechanisms, in whole or in part, as good or poor electrical conductors.

What I claim is:

1. Controlling or selecting mechanism such as used for single or multi-switches in telecommunication or similar installations comprising, a plurality of sets of two mutually perpendicular bars each movable in a longitudinal direction, a clutch member which is under the control of the first of said bars in the rest position and which is placed under the control of the second of said bars when said first bar moves into a working position, a controlling device placed under the control of said clutch member when said first bar moves into a working position whereby dis-

placements of said second bar in one sense or the other will cause said controlling device to be actuated by said clutch member and to be displaced to one out of two positions according to

5 the sense of displacement of said second bar, thereby acting directly or indirectly upon the device to be controlled, means being provided to return said control device to the rest position when said second bar returns to the rest position.

10 2. Controlling or selecting mechanism as claimed in claim 1, wherein said controlling device comprises a lever with two arms, the first being used to act upon the device to be controlled, the second having a forked or similarly shaped end designed to receive said clutch member when said first bar moves into a working position.

15 3. Controlling or selecting mechanism as claimed in claim 2, wherein after said controlling device has been actuated by said clutch member, the latter is maintained in a working position by said second bar, said first bar being able to return to a rest position and be used for other controlling or selecting operations.

20 25 4. Controlling or selecting mechanism as claimed in claim 3, wherein each of said first bars is displaced between two fixed bars parallel to the first bars, whereby when said clutch member is displaced under the control of said first bar, it is guided between the two adjacent surfaces of said parallel fixed bars and when it is displaced under the control of said second bar, it is guided between the forked end of said controlling device and a surface of one of the adjacent parallel fixed bars, perpendicular to said adjacent surfaces.

30 35 5. Controlling or selecting mechanism as claimed in claim 4, wherein each of said second bars, when displaced, slides on top of a parallel fixed bar, the upper side of which is inclined in such a manner that after said first bar has returned to the rest position and as soon as said second bar returns to the rest position, said clutch member rolls or slides along said inclined upper side to return under the control of said first bar.

40 45 6. Controlling or selecting mechanism as claimed in claim 5, wherein all of said fixed bars parallel to said second bars are fixed to the fixed bars parallel to said first bars, the latter fixed bars being fixed on both sides of a fixed supporting plate.

GEORGES XAVIER LENS.
